Primary Examiner—Jeffrey Asch*Assistant Examiner*—Bridget L. Eland(74) *Attorney, Agent, or Firm*—Thomas, Kayden, Horstemeyer & Risley(57) **CLAIM**

The ornamental design for a cellular phone, as shown and described.

DESCRIPTION

FIG. 1 is a front, side perspective view of a cellular phone showing our new design with the lid in an open position;

FIG. 2 is a front elevational view thereof;

FIG. 3 is a rear elevational view thereof;

FIG. 4 is a left elevational view thereof;

FIG. 5 is a right elevational view thereof;

FIG. 6 is a top elevational view thereof;

FIG. 7 is a bottom elevational view thereof;

FIG. 8 is a front, side perspective view of a cellular phone showing out new design with the lid in a closed position;

FIG. 9 is a front elevational view thereof;

FIG. 10 is a rear elevational view thereof;

FIG. 11 is a left elevational view thereof;

FIG. 12 is a right elevational view thereof;

FIG. 13 is a top elevational view thereof; and,

FIG. 14 is a bottom elevational view thereof.
